C. Harris and P. W. Joiner, of Cincinnati, Ohio.
Letters Patent No. 23337 - Dated June 12th 1866.
Design for a Cook's Stove.

The schedule referred to in the Letters Patent and making part of the same
To all whom it may concern

To be it known that we, C. Harris and Paul W. Joiner, both of Cincinnati, County of Hamilton
State of Ohio, have invented a new and improved design for Cook's Cooking Stoves, lately known and called the Atlanta... and we do hereby declare that the following is a full and exact description thereof, referenced being had to the accompanying photographs, and to letters of reference marked theron. Letter A. showing a perspective view of the stove.

What we claim as our invention and desire to secure by letters patent is the design for Cook's Cooking Stoves as shown and described.
